US0D1005620S

(12) **United States Design Patent** (10) **Patent No.:** **US D1,005,620 S**
(45) **Date of Patent:** **** Nov. 21, 2023**

(54) **DOG WATER RAMP**

(71) Applicant: **Albie's LLC**, Farmington, UT (US)

(72) Inventor: **Dominic Roque James Centorbi**,
Brooklyn, NY (US)

(**) Term: **15 Years**

(21) Appl. No.: **29/879,297**

(22) Filed: **Jul. 5, 2023**

(51) LOC (14) Cl. **30-03**

(52) U.S. Cl.

USPC **D30/199**

(57) **CLAIM**

The ornamental design for a dog water ramp, as shown and described.

DESCRIPTION

FIG. 1 is a top perspective view of a dog water ramp showing my new design;

FIG. 2 is a back side view thereof;

FIG. 3 is a front side view thereof;

FIG. 4 is a right side view thereof;

FIG. 5 is a left view thereof;

FIG. 6 is a top view thereof; and,

FIG. 7 is a bottom view thereof.

The dash-dash broken lines in the drawings depict portions of the dog water ramp that form no part of the claimed design.
